UNITED STATES PATENT OFFICE.

LESLIE R. PATTERSON, OF KANSAS CITY, MISSOURI.

DESIGN FOR A RUG.

Application filed November 16, 1923. Serial No. 7,781. Term of patent 14 years.

To all whom it may concern:

Be it known that I, LESLIE R. PATTERSON, a citizen of the United States, residing at Kansas City, Jackson County, Missouri, have invented a new, original, and ornamental Design for Rugs, of which the following is a specification, reference being had to the accompanying drawing, forming part thereof.

The figure is a plan view of a rug showing my new design.

I claim:

The ornamental design for a rug, as shown.

LESLIE R. PATTERSON.
